(57) **CLAIM**

The ornamental design for a pipette tip tray, as shown and described.

DESCRIPTION

FIG. 1 is a top, front perspective view of the first embodiment of a pipette tip tray with lid in a closed position; FIG. 2 is a bottom, front perspective view thereof; FIG. 3 is a top view thereof;

FIG. 4 is a bottom view thereof;

FIG. 5 is a front view thereof;

FIG. 6 is a back view thereof;

FIG. 7 is a side view thereof;

FIG. 8 is a side view thereof;

FIG. 9 is a front, top perspective view of the first embodiment of the pipette tip tray with lid in an open position; FIG. 10 is a bottom perspective view thereof;

FIG. 11 is a top view thereof;

FIG. 12 is a bottom view thereof;

FIG. 13 is a front view thereof;

FIG. 14 is a back view thereof;

FIG. 15 is a side view thereof; and

FIG. 16 is a side view thereof.

FIG. 17 is a top, front perspective view of the second embodiment of a pipette tip tray, with lid in a closed position;

FIG. 18 is a bottom, front perspective view thereof;

FIG. 19 is a top view thereof;

FIG. 20 is a bottom view thereof;

FIG. 21 is a front view thereof;

FIG. 22 is a back view thereof;

FIG. 23 is a side view thereof;

FIG. 24 is a side view thereof;

FIG. 25 is a front, top perspective view of the second embodiment of the pipette tip tray with lid in an open position;

FIG. 26 is a bottom perspective view thereof;

FIG. 27 is a top view thereof;

FIG. 28 is a bottom view thereof;

(Continued)

FIG. 29 is a front view thereof;
 FIG. 30 is a back view thereof;
 FIG. 31 is a side view thereof; and,
 FIG. 32 is a side view thereof.
 The broken lines of the drawings depict portions of the first and second embodiments of the pipette tip tray that form no part of the claimed design.
